BRUSH ARRANGEMENT FOR DISK-SHAPED COMMUTATORS.

1,400,779.

Specification of Letters Patent. Patented Dec. 20, 1921.

Application filed January 15, 1921. Serial No. 437,606.

To all whom it may concern:

Be it known that I, HERMANN SUNDHAUSSEN, residing at Essen, Germany, a citizen of the German Republic, have invented a certain new and useful Improvement in Brush Arrangements for Disk-Shaped Commutators, (for which I have filed application in Germany Jan. 17, 1917,) of which the following is a specification.

10 This invention relates to the arrangement of the brushes for disk-shaped commutators of electric machines. More particularly, it is the object of this invention to produce a brush arrangement in which the brushes 15 will come to exert a practically equally powerful and uniform pressure upon the disk-shaped commutator and will even when worn down, operate almost sparklessly.

The invention will be further described 20 with reference to the accompanying drawing which shows one embodiment of the subject matter of the present invention as applied to a vertical and cardanically suspended gyroscope motor by way of example. In 25 this drawing

Figure 1 is a top view, partly in section, of the brush arrangement together with the respective parts of the gyroscope motor,

30 Fig. 2 is a pertinent side elevation, looking from the left and partly in section on line 2—2 in Fig. 1, and

Fig. 3 is a section on line 3—3 in Fig. 1, looking from the left.

Referring to this drawing, A denotes the 35 gyroscope body containing the armature of a gyroscope motor, and rotatably lodged on its vertical shaft a^1 within an upright Cardan ring B. The gyroscope motor is provided with a disk-shaped commutator a^2 arranged at the upper end of the gyroscope body. The upright Cardan ring B has two arms b^1 extending in opposite directions, to each of which is rigidly fixed a pivot B^2 crossing the commutator shaft at right 45 angles. The axes of said two pivots B^2 are located in parallel to each other. On the stepped free end b^3 of each pivot B^2 , there is mounted a revoluble sleeve C of outer square shape (shown more clearly in Fig. 50 3), which for its part is provided with a flange c^1 bearing up against the stouter part

of the pivot B^2 . On each sleeve C is placed a second sleeve D of box-shaped cross section and made of a non-conducting material, and which is adapted to support the two-part brush holders E, as also two disks F of a non-conducting material forming the lateral confines of said brush holders. The sleeve C along with all the parts borne by it, are secured against shift in the manner disclosed in the drawing, namely by aid of a washer and a screw nut. Each brush holder E is fitted with two arms e^1 within which there is lodged to rock on two coaxially disposed pivots g^2 , the sleeve G^1 supporting the brush G. The axis of the pivots g^2 is disposed in parallel to the axis of the pivots B^2 b^3 forming the axis of oscillation of the brush holder E. As will be seen from the drawing, the arrangement devised is such that the two brush holders E as well as their brushes G will come to be disposed along one and the same diameter of the commutator a^2 on either side of the commutator shaft a^1 .

On the stouter portion of each of the pivots B^2 there is loosely mounted so as to be capable both of rotation and displacement an annular body H. These two annular bodies H are slotted in the manner disclosed in the drawing (Fig. 1) and are connected with each other by an initially tensioned spring J the ends of which are attached to pins h^1 fixed in the annular bodies H. The common spring J consequently 80 comes to apply a turning moment on both annular bodies H, the arrangement devised being such that the active lever of said turning moment will augment when the annular bodies H are rotated in the direction indicated by arrow α (Fig. 2), which moment causes a reduction in the tension force of the spring. By these means the result is secured that the turning moment exerted by the spring will approximately retain its 85 value. The annular bodies H subjected to the action of the common tension spring are connected to the sleeves C each by means of a pin h^2 (Fig. 1) screwed into each annular body H. The pin h^2 projects with its 90 head h^3 through a recess c^2 formed in the flange c^1 of the sleeve C and bears up in the 95 100

manner shown in Fig. 1 under the action of the spring J against the wall of said recess. The annular body H, the pin h^2 with its head h^3 and the recess c^2 of the sleeve C form the parts of a disconnectible coupling intermediate the spring J and the brush holder E.

In the position of the several parts of the brush arrangement as shown, the spring 10 J exerts on the two annular bodies H a turning moment which substantially remains the same even when the spring tension diminishes, and which tends to rotate the annular bodies in the direction indicated 15 by the arrows α (Fig. 2). The turning moment is transmitted by the pin h^2 , acting as the engaging member, upon the sleeve C and therewith upon the brush holders E which, as a result, likewise tend to turn in 20 the sense denoted by the arrows α and in so doing press the brushes G with equal force down upon the slide surface of the disk-shaped commutator a^2 .

When it be desired to inspect the sliding 25 surface of a brush, or to replace a brush, the appropriate annular body H is rotated counter to the direction indicated by the arrow α for such an extent that the pin h^2 can be withdrawn from the recess c^2 . Here- 30 upon the annular body H is axially displaced for such a distance that the coupling existing between it and the sleeve C will be disconnected. To conclude, the respective 35 brush G along with its holder E is turned into the position indicated in dash-and-dot lines in Fig. 2 in which position the brush may be conveniently inspected or taken out and replaced.

From the improved brush arrangement 40 hereinbefore-described it will be understood that both brushes are also pressed close up and absolutely uniformly on both sides of the commutator shaft against the commutator even in case the brushes have already 45 been worn down. This feature embodies the advantage that any one-sided pressure of the brushes upon the commutator will be obviated with certainty.

But besides this, the improved brush arrangement offers the advantage that despite 50 the unevenness in the wearing down of the brushes resulting from the disparity in the peripheral speed of disk-shaped commutators, the brushes will be enabled to operate 55 almost sparklessly and that a practically constant intermediate resistance will always be secured. This advantage is founded on the fact that, owing to the more rapid wear of the outer portions of the brushes, the latter will rotate about their pivots g^2 , impelled by the action of the turning moment exerted by the spring J, and will adjust 60 themselves so that, exactly as in the case of brushes not worn down, the entire collecting surface thereof will always come to bear 65

up against the slide face of the commutator.

Moreover, owing to the oscillating pivots of the brush holders being firmly fixed in their position, the brush arrangement forming the subject matter of this invention 70 further offers the security against any undesirable shifting of the brushes out of the neutral zone.

Claims:

1. An arrangement of the class described 75 in combination with a motor and a disk-shaped commutator comprising a pair of arms secured to the motor, a pair of pivot bars projecting therefrom, brush holders mounted on said pivot bars, brushes pivotally supported by said holders, said holders being disposed at right angles to the commutator axis and on opposite sides thereof and spring means connecting said holders, said spring tending to rock said brushes toward said commutator.

2. An arrangement of brushes for use in combination with a motor having a disk-shaped commutator comprising arms rigidly secured to said motor, a pair of parallel 90 pivot bars secured to said arms, a pair of brush holders rotatably supported on said pivot bars and arranged at opposite sides of said commutator, brushes pivotally supported by said holders, annular bodies on 95 said pivot bars, means connecting said annular bodies to said brush holders and a spring connecting said annular bodies tending to rotate them in a direction to cause said brushes to engage said disk-shaped 100 commutator.

3. An arrangement of brushes for use in combination with motors having disk-shaped commutators comprising a pair of arms rigidly secured to said motors, a pair 105 of spaced parallel pivot bars secured to said arms and disposed on opposite sides of the axis of said commutator, a pair of brush holders rotatably supported on said pivot bars, a pair of arms projecting from each 110 brush holder, a brush pivotally supported between each pair of arms, a pair of rotatable members mounted on said pivot bars adjacent said brush holders, a spring connecting 115 said pair of rotatable members and a disconnectible coupling connecting each rotatable member with its adjacent brush holder whereby the action of said spring tends to cause said brushes to constantly engage said disk-shaped commutator.

4. An arrangement for brushes in connection with a motor having a disk-shaped commutator comprising supporting means projecting from said motor, a pair of pivot bars projecting from said supporting means 125 and disposed parallel to each other and crossing the axis of the commutator at right angles thereto, a pair of brush holders rotatably supported on said pivot bars, said brush holders being each provided with a 130

pair of arms, a brush pivotally mounted in each pair of arms, a pair of rotatable members mounted respectively on said pivot bars and adjacent said brush holders, means connecting each rotatable member with its adjacent brush holder and a spring, the ends of which are attached respectively to said rotatable members, the point of connection of such spring with said rotatable members being such that when said brush holders are rocked in a direction corresponding to the relaxing of said spring the active lever of said spring will be increased.

The foregoing specification signed at Essen, Germany, this 6th day of December, 15 1920.

HERMANN SUNDHAUSSEN.
